LAMP HOLDER FOR ELONGATED FLUORESCENT LAMPS

Roger W. Haven, Winchester, Mass., assignor to Sylvania Electric Products Inc., Salem, Mass., a corporation of Massachusetts

Application February 28, 1946, Serial No. 650,970

1 Claim. (Cl. 173—328)

1

This invention relates to lampholders and more particularly to lampholders for electric discharge lamps of the tubular type.

An object of this invention is to provide a lampholder which will permit a quick and easy insertion of a lamp therein.

Another object is to provide a lampholder which will be cheap in cost yet sturdy enough in construction to be capable of withstanding the stresses to which it is subjected when the lamp is inserted and withdrawn.

Further objects, advantages, and features will be apparent from the following description when read in conjunction with the accompanying drawing in which:

Figure 1 is a front elevational view of the lampholder of my invention.

Figure 2 is a rear elevational view of the lampholder with the cover plate and one of the elongated contact fingers removed.

Figure 3 is a side elevational view of the lampholder and a fragmentary view of a discharge lamp in position in the lampholder.

Figure 4 is a sectional view taken through the center of the lampholder along its longitudinal axis with the elongated main reinforcing member and the elongated contact finger removed.

Considerable difficulty has been experienced in attempting to develop a satisfactory lampholder for fluorescent lamps. A great portion of this difficulty can be traced ultimately to the fact that when a person rotates the lamp to disengage the pins thereof from their operating position to permit the lamp to be removed from its holders, he is not able to see the lamp pins. This inability to see the pins prevents the person from making sure that he is rotating the lamp properly. If the lamp has not been rotated to the proper position for withdrawal from its holders, and an attempt is made to remove it considerable stress is set up in the holders, and, many times they break or are weakened considerably.

Many lampholders have been designed for fluorescent lamps, some with the object of providing a holder which will prevent or minimize the possibility of damage thereto due to the above-mentioned conditions. However, I have found that, even with these holders, the problem has not been completely or adequately solved. I have, therefore, developed a lampholder which has proven to be highly satisfactory and successful in solving this problem.

The lampholder of my invention embodies the idea of providing a body member with an opening in its front face for the reception therein of

2

lamp pins, said opening defining a substantially triangular recess with a truncated apex in the body member, with the exception that two of the sides of the defined recess are curved in contour.

5 The lampholder of my invention embodies the additional idea of connecting to the body member a stud or pin which is caused to project into the central portion of the afore-mentioned opening or recess in the face of the body member. 10 This stud or pin is substantially triangular in contour with the sides thereof curved slightly and the three corners rounded sharply. The base of the triangular stud or pin and the base of the recess in the body member of the lampholder are 15 spaced from each other and form a channel through which the lamp pins may pass.

The lampholder 1 of my invention comprises a hollow body member 2 having an opening 3 in its front face, said opening defining a substantially triangular recess with a truncated apex 4, the sides 5 adjacent thereto being curved and the base 6 being straight. The hollow body member 2 is provided with an elongated reinforcing member 7 which is disposed in the center thereof 20 along its longitudinal axis. The top of the member 7 is provided with a substantially triangular stud 8 which projects into the center of the opening 3 in the front face of the body member 2. The sides 9 of the stud 8 are slightly curved, the 25 corners 10 thereof are curved sharply and the base 11 of the stud is straight.

A pair of elongated contact fingers 12 are disposed within the body member 2 (Figures 1 and 2). When a lamp 13 (Figure 3) is inserted in 30 the lampholder 1, the contact pins 14, projecting from the ends of the lamp, extend through the opening 3 in the face of the body member 2 and establish a firm positive contact with the fingers 12, intermediate one end thereof. Each contact 35 finger 12 is provided with a screw 15, intermediate the other end thereof, to which a source of electric power may be connected. Each contact finger 12 is characterized by a notch 16 to provide a suitable seat for a contact pin 14 on a lamp 13 when the lamp is positioned in the lampholder. Each contact finger 12 is further provided with a slot therein which, when the contact finger is positioned in the body member 2, is engaged by the rib 17 in the body member (Figures 45 2 and 4). This feature of construction aids in preventing movement of the contact finger along its longitudinal axis. Each contact finger 12 is also provided with two raised portions 18, one 50 near the notch 16 and the other at the end adjacent the screw 15. This feature of construction

also aids in the firm, positive seating of the contact fingers in the body member. When a base plate (not shown) is attached to the back of the body member by means of screws, rivets or the like which may be driven into the holes 19 in the reinforcing member 7 (Figure 2) to cover the rear of the body member 2, a firm, positive contact is established by the base plate with the raised portions 18.

The contact fingers 12 also possess a locking feature which corrects a highly undesirable condition which has existed in fluorescent lamp installations. Fluorescent lighting has been used extensively in many industrial establishments. Quite frequently, in installations of this type, the lamps and the fixtures in which they are installed are subjected to considerable shock due to vibrations set up by operating machinery.

Many times this continuous vibration jars the lamp pins from their sockets and the lamp falls out of the fixture. The lampholder of my invention has been designed to eliminate this hazardous condition.

The contact fingers 12 are seated in the hollow body member 2 with the upper portion of each finger exposed by the opening 3. That portion of each contact finger 12 which extends above the notch 16 is disposed with respect to the sides 9 of the stud 8 so that at one point the distance between a contact finger 12 and the adjacent side 9 of the stud 10 is less than the diameter of the pins projecting from the ends of a lamp. Thus if a lamp pin were jarred from its normal position within a notch 16 the lamp could not fall out of the socket because a definite positive force would have to be exerted on the lamp to spring the contact finger 12 to permit the pin to pass this constriction.

The sides 20 of the body member are provided with elongated reinforcing strips 21 to aid in stiffening and strengthening the body member. To these strips 21 webs 22 are connected. Excessive movement laterally of the contact fingers 12, when normally disposed within the body member 2, is prevented by the webs 22 which engage one side of the fingers and the lower portion of the elongated reinforcing member 7 which is provided with an abutment 23 which engages the other side of the fingers (see Figure 2).

The lampholder 1 is provided with a base 24 which is in turn provided with a centrally disposed seat 25 for the disposition therein of means for mounting the lampholder, and two apertures 26, one on each side of the seat 25, through which wires may be inserted to establish an electrical connection from a power source to the screws 15 on the contact fingers 12 (Figures 1 and 2).

An additional strengthening and reinforcing feature of the lampholder is embodied in the arch 27 which extends across the top of the body member 2.

The top of the body member is also provided with a truncated substantially V-shaped opening 28 which facilitates the guidance of the lamp pins 14 into and out of the recess 3 in the face of the body member 2. The truncations of the substantially V-shaped opening 28 and the substantially triangular recess 3 are substantially coextensive.

When it is desired to insert a lamp into the holder of my invention, the pins projecting from the ends of the lamp are brought into vertical alignment with the opening 28 and guided therethrough into the recess 3. The sharply tapered corners 9 of the stud 8 will direct the lead pin to the right or to the left of the stud into one of

the channels 29 defined by the curved sides 9 of the stud 8 and the curved sides 5 of the recess 3. When the lead pin of the lamp engages the notch 16 in a contact finger 12, the other pin of the lamp is disposed at the top of the recess 3. The lamp is then rotated to cause the other pin to pass through the other channel 29 and into the notch 16 in the other contact finger 12, thus securely seating the lamp within the lampholder and establishing a positive contact with the elongated contact fingers 12.

When it is desired to remove a lamp from the holder of my invention, the lamp is rotated sufficiently to disengage one of its pins 14 from its normal operating position in a notch 16 in a contact finger 12 and cause it to move through one of the channels 29 to a position substantially at the truncated apex of the recess 3. The lamp may then be withdrawn from its holder through the truncated substantially V-shaped opening 28, the other pin 14 of the lamp traveling up through the other channel 29 and through the opening 28.

If the lamp is accidentally rotated too much during the first step in removal so as to cause the lead pin of the lamp to travel up through one channel 29, past the truncated apex of the recess 3 and down into the other channel 29, no damage can be wrought to the lamp holder because as soon as the lead pin starts to move into the second channel 29 the other pin will start to move through a channel 30 defined by the base of the stud 8 and the base of the recess 3. When this occurs, rotation may be continued until the other pin travels through channels 30 and 29 and the lamp withdrawn or the lamp may be rotated in the reverse direction until the original lead pin is brought back to the truncated apex of the recess 3 and the lamp may then be withdrawn in the manner described above.

The ease with which a lamp may be inserted or withdrawn and the structural features which make it practically fool-proof insofar as the possibility of damage thereto as a result of improper insertions or withdrawals is concerned, make the socket of my invention an extremely practical and desirable product.

The curved sides 5 of the recess 3 and the slightly curved sides 9 of the stud 8 form arcuate channels 29 which provide especially convenient paths for the passage of the contact pins 14 on a lamp 13. The possibility of any binding due to improper manipulation of the lamp while it is being inserted or withdrawn from the holder is substantially reduced by the sharply rounded corners 10 of the stud 8.

The advantages of the holder of my invention may be appreciated more fully when it is realized that the configuration of that portion of the holder with which the lamp pins come in contact is characterized by a plurality of curved sides and sharply rounded edges, all tending to obviate the possibility of any binding due to improper manipulation of the lamp during its installation in or removal from its holder.

What I claim is:

A holder for an electric discharge device having two contact pins at one end thereof, said holder comprising: a body member of insulating material having a flat surface with an opening 70 therein substantially triangular in contour with at least two of its sides curved and the apex angle truncated, and a truncated, substantially V-shaped opening in said body member above said first-mentioned opening, the truncations of the 75 two openings being coextensive; a stud of in-

sulating material connected to the body member and projecting into the central portion of the first-mentioned opening, said stud being substantially triangular in contour with at least two of its sides curved and the corners rounded, the sides of said stud and the walls of said three-sided opening defining three channels through which the contact pins of said electric discharge device may travel; and two electrical contact members disposed within said body member, a 10 portion of each contact member being exposed by the first-mentioned opening and adapted to be engaged by contact pins on an electric discharge device when said device is inserted in the holder.
